(57) **CLAIM**

The ornamental design for a bed riser assembly, as shown and described.

DESCRIPTION

FIG. 1 is a left, front, and top perspective view of a bed riser assembly, showing my new design;

FIG. 2 is a left, front and top perspective view thereof, shown in a disassembled configuration of use with bottom portion removed for clarity of disclosure;

FIG. 3 is a left, front, and top perspective view thereof, shown in a disassembled configuration of use with the top portion removed for clarity of disclosure;

FIG. 4 is a front elevation view of the bed riser assembly, as shown in FIG. 1;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an exploded view thereof; viewed from left, front, and top.

The broken lines depict portions of the bed riser assembly that are not included in the claimed design.
